AUTOMOBILE RADIATOR GRILLE AND HOUSING

Richard C. Le Bron, Omaha, Nebr.

Application August 25, 1958, Serial No. 52,351

Term of patent 3½ years

(Cl. D14—18)

Fig. 1.

Fig. 2.

Figure 1 is a front elevational view of an automobile radiator grille and housing showing my new design; and Figure 2 is a perspective view thereof.

The automobile is shown in broken lines for purpose of illustration only.

I claim:

The ornamental design for an automobile radiator grille and housing, as shown and described.
